Application filed March 17, 1890. Serial No. 344,239. Term of patent 3½ years.

To all whom it may concern:

Be it known that I, HENRY MILLER, a citizen of the United States, residing at Pittsburgh, in the county of Allegheny and State of Pennsylvania, have invented certain Designs for Paper-Weights; and I do hereby declare the following to be a full, clear, and exact description of the invention, reference being had to the accompanying drawing, which forms part of this specification.

My invention has relation to designs for glass paper-weights; and it consists of a sphere flattened on one side and containing an image of a bouquet or group of flowers composed of a large central flower surrounded by flowers of smaller size arranged somewhat below the central flower, each flower being provided with a bulbous pistil, in conventional representation or imitation of a drop of dew.

In the illustration accompanying this specification I have shown a paper-weight consisting of a sphere A, flattened on one side, as at a, and containing an image of a bouquet of flowers consisting of a large central flower B and smaller flowers b b b, grouped around and below the flower B, each flower of the bouquet being provided with a bulbous pistil c.

Having described my design, I claim—

The design for a glass paper-weight herein shown and described, consisting of a truncated sphere containing an image of a bouquet of flowers, each flower being provided with a bulbous pistil, as set forth.

In testimony that I claim the foregoing I have hereunto set my hand this 7th day of March, 1890.

HENRY MILLER.
